DESIGN.

G. H. GRIFFITH.

LEAGUE BUTTON.

APPLICATION FILED JAN. 29, 1919.

53,365.

Patented May 27, 1919.

INVENTOR:

George H. Griffith.

BY his ATTORNEY:

Thomas C. Spelling

UNITED STATES PATENT OFFICE.

GEORGE H. GRIFFITH, OF ST. PAUL, MINNESOTA, ASSIGNOR TO ARTHUR C. TOWNLEY, WILLIAM LEMKE, AND FRANK B. WOOD, ALL OF FARGO, NORTH DAKOTA, AS MEMBERS OF THE EXECUTIVE COMMITTEE OF THE NATIONAL NONPARTISAN LEAGUE.

DESIGN FOR A LEAGUE-BUTTON.

53,365.

Specification for Design.

Patented May 27, 1919.

Application filed January 29, 1919. Serial No. 273,924. Term of patent 14 years.

To all whom it may concern:

Be it known that I, GEORGE H. GRIFFITH, a citizen of the United States, residing at St. Paul, in the county of Ramsey and State of Minnesota, have invented a new, original, and ornamental Design for League-Buttons, of which the following is a specification.

In the accompanying drawing the figure is a front or face view of the button showing my new design.

What I claim is:

The ornamental design for a league button as shown.

In testimony whereof, I affix my signature.

GEO. H. GRIFFITH.
